HEATER

Henry J. De N. McCollum, Chicago, Ill.; Thelma McCollum executrix of said Henry J. De N. McCollum, deceased

Application February 18, 1943, Serial No. 476,266

11 Claims. (Cl. 126—116)

1

My invention relates to heaters and more particularly to heaters of the internal combustion type.

An object of my invention is to provide an internal combustion type of heater having improved means for obtaining thorough vaporization of the liquid fuel.

Another object of my invention is to provide new and improved means for imparting any desired degree of preheating to the combustible mixture.

Another object of my invention is to provide a new and improved heater wherein the foregoing objects are accomplished by a structure which is compact, light in weight, inexpensive to manufacture, and trouble-free in use.

Other objects and advantages will become apparent as the description proceeds.

In the drawing:

Fig. 1 is a longitudinal, sectional view of a preferred form of heater embodying one form of my invention; and

Fig. 2 is a partial, transverse section taken on the line 2—2 of Fig. 1.

In Figs. 1 and 2, I have illustrated a preferred form of my invention comprising a heater having an air inlet 10 adapted to be supplied with air from a ram, blower, or any other suitable source of air supply. A part of the air entering the inlet 10 passes into a Venturi tube 12, having a fuel jet 14 provided with radial passages 16 in the throat of the Venturi tube. The jet 14 is supplied with any suitable liquid fuel, such, for example, as gasoline or kerosene from any suitable source of fuel supply and the fuel discharged from the passages 16 in the jet 14 mixes with the air entering the lefthand or inlet end of the Venturi tube 12 to form a combustible mixture.

This mixture passes from the outlet or righthand end of the Venturi tube 12, through a wire screen 18 into the fibrous material 20 contained in a sheet metal cannister 22 having an opening 24 in registry with the outlet end of the Venturi tube 12. The fibrous material 20 may be stainless steel wool or glass wool, or a mixture of stainless steel wool and glass wool, or any other suitable material.

As the combustible mixture passes through the fibrous material, the fuel and air are thoroughly mixed and may be preheated to any desired degrees, as hereinafter explained. The combustible mixture flows through the outlet openings 26 in the righthand end of the cannister 22 and passes into a combustion chamber 28 where it is initially ignited by an electrical igniter 30, or any other

2

suitable means. The igniter 30, in accordance with usual practice, may be disconnected from its source of current by a thermostatic switch after the heater attains normal operating temperature and I provide a re-igniter 32 to maintain combustion after the igniter 30 has been cut out.

The hot gases resulting from the combustion in the combustion chamber flow into the righthand ends of the longitudinally extending flues 34 formed in a cylindrical heat exchanger indicated generally by reference character 36 and pass from the lefthand end of these flues into an outlet chamber 38. An outlet fitting 40 is fixed in a wall of the chamber 38 and has a threaded end 42 to which any suitable exhaust pipe may be connected whereby the cooled gases may be discharged from the outlet chamber 38 through fitting 40 and the exhaust pipe connected thereto.

20 The heat exchanger 36 comprises a corrugated sheet 44 of aluminum or other suitable material bent into the form of a cylinder and having its contacting edges welded to form a seamless tube. Fins 46 of aluminum or other 25 suitable material are welded or otherwise secured in the folds 48 formed in the aluminum sheet 44 between the flues 34. The fins 46 are in the form of sheet metal strips having their outer edges serrated, as indicated at 50, to divide the radially 30 outward portions of the strips 46 into a plurality of fingers 52 to increase the rate of heat transfer from the fins to ventilating air directed thereover in a manner hereinafter described.

A tubular muffler 54 is located inside of the aluminum sheet 44. This muffler comprises an outer shell 56 and sound absorbing material 58, such as stainless steel wool or glass wool, located between the shell 56 and the sheet metal cannister 22 which forms the inner wall of the muffler. The shell 56 is provided with openings 60 which form acoustic couplings between the interior of the shell 56 and the flues 34, whereby sound may enter the shell 56 and be absorbed by the material therein. While the muffler proper consists of only a relatively thin layer of sound absorbing material arranged in the form of a tube, I have found that such a thin layer absorbs all of the objectionable sound and is entirely satisfactory.

40 The heater is provided with a cylindrical casing 62 which surrounds the heat exchanger 36 and directs ventilating air thereover. The lefthand end of the cylindrical casing 62 communicates with the inlet 10 by way of tapered passage 64 formed between an outer sheet metal cone 66 and an inner sheet metal cone 68. The right-

hand end of the casing 62 may communicate directly with the airplane cabin or other space to be heated, or may be connected to a duct system having several outlets placed at selected locations to distribute the heated ventilating air to several portions of the same space or to separate spaces.

The ends of the aluminum sheet 44 of the heat exchanger 36 are illustrated as being located in grooves formed in rings 70 and 72, which form a convenient means for supporting this plate and associated parts. The ends of the plate 44 are sealed to the rings 70 and 72 by welding, or otherwise, to prevent leakage of the products of combustion into the passageways for the ventilating air. The ring 70 is attached to and supported by the cone 68, whereas the ring 72 is attached to and supported by the end wall 74 of the combustion chamber 28.

Stainless steel wool is a relatively good heat conductor, whereas glass wool is a relatively poor heat conductor. When a heavy fuel is used, or when, for any other reason, a relatively great amount of preheating is desired, the muffler shell 56 and cannister 22 can be filled with stainless steel wool. On the other hand, when substantially no preheating is desired, the muffler shell and cannister can be filled with glass wool. When some intermediate degree of preheating is sought, part of the space in the muffler and cannister can be filled with stainless steel wool and the other part with glass wool and in this manner any desired degree of preheating can be obtained.

In my invention the combustible mixture formed in the carburetor is first passed through fibrous material which insures vaporization of all of the liquid fuel and thorough mixing of the vaporized fuel and air before this combustible mixture enters the combustion chamber. In my invention the fibrous material is exposed to heat created in the burner and by proper selection of the particular kind or kinds of fibrous material used, any desired degree of preheating of the combustible mixture may be provided. These features render my novel heater particularly adapted for use with different fuels such, for example, as gasoline, kerosene and fuel oil, since these fuels require different degrees of preheating to burn efficiently. The length of the fibrous path through which the combustible mixture flows before entering the combustible chamber can also be varied to afford just the right amount of preheating, vaporization and intermixing of the fuel and air before this fuel enters the combustion chamber to adapt the heater to any particular fuel or to satisfy special operating conditions.

The foregoing advantages are attained in a structure which is compact, light, inexpensive to manufacture and which requires a minimum of service attention. This heater is particularly adapted for use in aircraft, but is not limited to such use and is capable of general application.

While I have described only one embodiment of my invention, it is to be understood that my invention is not limited to the particular details shown and described, but may assume numerous forms and that the scope of my invention is defined in the following claims.

I claim:

1. A heater comprising a combustion chamber, a heat exchanger communicating with said combustion chamber and heated by products of combustion therefrom, means for supplying a com-

bustible mixture to said combustion chamber, said means including a Venturi tube, and means forming a passage through said heat exchanger filled with fibrous material interposed between said combustion chamber and said venturi tube and through which the combustible mixture must pass before entering the combustion chamber, part of said fibrous material being located immediately adjacent the end of said Venturi tube.

2. A heater comprising a combustion chamber, a heat exchanger receiving products of combustion from said combustion chamber, means for directing ventilating air over said heat exchanger, a carburetor for supplying combustible mixture to said combustion chamber, means forming a passage through said heat exchanger interposed between said carburetor and said combustion chamber, and steel wool in said passage for preheating, vaporizing and intermixing the fuel and air in said combustible mixture prior to the entry of this mixture into the combustion chamber.

3. In a heater of the class described, the combination of a heat exchanger, a combustion chamber located at one end thereof, a carburetor located at the other end of said heat exchanger, fibrous material interposed between said carburetor and combustion chamber in heat exchanger relation with said heat exchanger and through which combustible mixture supplied by said carburetor must pass before entering such combustion chamber, said fibrous material preheating, vaporizing and intermixing the fuel and air in the combustible mixture prior to its entry into said combustion chamber, and means for directing ventilating air over said heat exchanger.

4. A heater of the class described, comprising a tubular heat exchanger, a casing enclosing said heat exchanger, said casing having an inlet for ventilating air adjacent one end of said heat exchanger, a carburetor at said end of the heat exchanger and receiving air from said inlet, a combustion chamber at the opposite end of said heat exchanger for supplying products of combustion thereto, means forming a passage located in said heat exchanger and affording communication between said carburetor and combustion chamber, fibrous material located in said passage, a muffler interposed between said passage and said heat exchanger, and an exhaust chamber surrounding said carburetor and receiving products of combustion from said heat exchanger.

5. A heater of the class described, comprising a tubular heat exchanger, a combustion chamber for supplying hot products of combustion to said heat exchanger, said muffler located in said heat exchanger, said muffler comprising inner and outer tubular shells forming a space therebetween filled with sound absorbing material, and means for supplying a combustible mixture to said combustion chamber through the tubular inner shell of said muffler.

6. A heater comprising a combustion chamber, a heat exchanger receiving products of combustion from said combustion chamber, means for directing ventilating air over said heat exchanger, a carburetor for supplying combustible mixture to said combustion chamber, means forming a passage through said heat exchanger interposed between said carburetor and said combustion chamber, and glass wool in said passage for preheating, vaporizing and intermixing the fuel and air in said combustible mixture prior

to the entry of this mixture into the combustion chamber.

7. A heater of the class described, comprising a heat exchanger, a combustion chamber for supplying products of combustion to said heat exchanger, a muffler located in said heat exchanger, stainless steel wool in said muffler, said muffler having means forming a passage therethrough, means for supplying a combustible mixture to said combustion chamber through said passage, and steel wool located in said passage.

8. In a heater of the class described, the combination of a heat exchanger, a combustion chamber for supplying hot products of combustion to said heat exchanger, a tubular muffler located in said heat exchanger, means for supplying a combustible mixture to said combustion chamber through said muffler including fibrous material within said muffler through which said combustible mixture passes as it travels the length of said muffler.

9. A heater of the class described, comprising a heat exchanger, means for directing ventilating air over said heat exchanger, a combustion chamber for supplying hot gases to said heat exchanger, a carburetor for supplying combustible mixture to said combustion chamber, means interposed between said carburetor and combustion chamber and forming a passage therebetween and through said heat exchanger, said means having a plurality of openings connecting

said passage with said combustion chamber, fibrous material located in said passage, and a metal screen interposed between said carburetor and said passage.

5 10. A heater comprising a heat exchanger, a combustion chamber for supplying hot gases to said heat exchanger, a muffler in said heat exchanger, means for supplying combustible mixture to said combustion chamber, means forming a passage through said muffler connecting said means with said combustion chamber, said passage and muffler providing separate spaces, fibrous material in said spaces and comprising stainless steel wool in one of said spaces and glass wool in the other of said spaces to proportion the amount of preheating of the combustible mixture.

15 11. A heater of the class described, comprising a tubular heat exchanger, a combustion chamber for supplying hot gases to said heat exchanger, and a muffler in said heat exchanger, said muffler comprising inner and outer tubular shells affording an annular space therebetween which is radially narrow as compared to the 20 radius of said outer shell, sound absorbing material between said shells, and means for supplying a combustible mixture to said combustion chamber through said inner tubular shell, said combustible mixture being preheated as it passes 25 therethrough.

30 HENRY J. DE N. MCCOLLUM.
